PILOT CUT-OFF FOR GAS BURNERS

Filed Sept. 16, 1927

Inventor
Rufus H. Maurer
by Roberts Cushman & Woodbury,
Att'ys.

UNITED STATES PATENT OFFICE.

RUFUS H. MAURER, OF BROOKLINE, MASSACHUSETTS, ASSIGNOR TO SPENCER THERMOSTAT COMPANY, OF CAMBRIDGE, MASSACHUSETTS, A CORPORATION OF MASSACHUSETTS.

PILOT CUT-OFF FOR GAS BURNERS.

Application filed September 16, 1927. Serial No. 219,941.

This invention relates to gas burners and more particularly to heating gas burners provided with pilots and with an automatic means of cutting off the flow of gas in the event that the pilot is extinguished.

Heating by gas is now very common for water heaters, boilers, stoves and domestic furnaces and it is customary in many of these installations to vary the heat applied by thermostatic or other means; so that as the burners are often relatively inaccessible, and it is customary to provide a pilot light adjacent to the burner if it is extinguished and it is desired to relight it. It sometimes happens that 10 during the time the main burner is extinguished by the thermostatic or other means, the pilot accidentally goes out, so that when the flow of gas to the main burner is re-established, it is not ignited, but escapes to the 15 surrounding parts of the building in which the burner is located.

Among the objects of the invention, therefore, are to provide an automatic shut-off which will function quickly and in a certain 20 manner to cut off the flow of gas to a heating burner to prevent gas leakage and the consequent danger to persons in the vicinity both from asphyxiation and fire in the event that the pilot goes out for any reason without the 25 gas supply being completely turned off; to provide a simple, cheap and efficient mechanism to accomplish the above results; and generally to improve devices of this character.

Other objects and advantages of the invention will be apparent from the following specifications and appended claims when taken in conjunction with the accompanying drawings, in which:

Fig. 1 is an elevation of the gas burner partly broken away to show the pilot, thermostatic and valve structure in vertical section;

Fig. 2 is a combined elevation and section on the line 2—2 in Fig. 1; and

Fig. 3 is an enlarged view of the thermostatic disk.

I have shown my invention in connection with an annular ring type gas or gas and air burner 1 having a plurality of series of opposed jet nozzles 2 and a gas inlet 3, but it 50 may equally well be applied to other types of burners. A pilot nozzle 4 is formed adja-

cent to one of the pairs of opposed nozzles 2 and serves to light them whenever they are supplied with gas. I provide a means for 55 cutting off the gas supply to the burner and a major part of the supply to the pilot whenever the latter is extinguished, such means preferably comprising a valve housing 5 having a threaded gas inlet opening 6 for connection with the usual gas or gas and air mixture supply pipe 7 and having a connection at 8 with an inlet opening 3 of the burner 1. The housing 5 is provided with a dividing wall 9 having a passage 10 therethrough adapted to be closed by a valve 11, which may be constructed of any suitable material, for example rubber, and may have a peripheral flange 12, which, when the valve is closed, is turned up, as shown at 12^a (Fig. 70 2). A rod 13 is fixed to the valve 11 by a nut engaging a reduced threaded extension of the rod 14 or in any other desired manner, and extends through a suitable bearing opening in the wall 9 and thence through an enlarged opening 15 in one side wall 16 of the housing 5. The wall 16 may be provided with an outwardly extending annular flange 17, threaded on its outer side for engagement with an enlargement 18, which may be integral with the pilot nozzle 4.

I provide thermostatic means in heat conducting relationship with the nozzle 4 of the pilot to actuate the rod 13 and open and close the valve. This thermostatic means is preferably a disk 19, which is engaged at its periphery between the flange 17 and a shoulder formed on the enlargement 18 and is perforated, as shown at 20, to permit the passage of gas therethrough to sustain the pilot light. 90 The rod 13 is connected to the center of the disk 19 by a nut 21 engaging a reduced threaded extension of the rod or in any other suitable manner.

The disk 20 is preferably bi-metallic, being 95 formed of two component disks welded together, the materials such as iron and brass of the respective disks having different coefficients of expansion. The disk 20 is normally cupped (as by swaging) in such direction that 100 the component part having the higher coefficient of expansion is on the concave side. Consequently upon raising the temperature of the disk the unequal expansion of the ma-

terials forming the disk will cause a tendency to flatten the cupped surface until at a pre-determined temperature a sudden curving in the opposite direction occurs, which reversal 5 of shape will be maintained until the temperature has been substantially lowered. Thereafter upon reaching a substantially lower temperature, the disk will suddenly return to its initial shape. The materials and 10 thickness of the component parts and the degree of curvature are so chosen that the disk will snap in one direction when heated to the desired temperature (e. g. 120° F.) and will snap back at a lower temperature (e. g. 100° F.). Suitable materials are sheet brass and nickel steel having a thickness of .005 and .005 inches respectively and suitable cupping for a disk $\frac{3}{4}$ inches in diameter is .02 inches.

It will be understood however that the 20 present invention is not limited to any particular combination of materials having different thermal coefficients of expansion but is intended to embrace in its scope any combination of materials having dissimilar 25 thermal coefficients of expansion sufficient to cause the reversal of curvature. Furthermore, the two materials comprising the composite thermostatic disk may be secured together in any desired manner by riveting, 30 soldering, brazing, or otherwise although it is preferred to unite the materials comprising the disk by welding or similar means to secure a substantially indivisible sheet.

I provide a separate independent source of 35 gas for the pilot light here shown as a supply duct 22 which may connect with the main gas pipe 7 at the other side of the valve shown, and which may be suitably fixed in the housing 5 by threading or in any other suitable 40 manner, the duct 22 being connected by a bore 23 with a space at one side of the thermostatic disk 19, so that the pilot will receive a constant supply of gas whether the burner is in 45 operation or not, and during the time it is in operation the pilot will receive a large supply of gas through the opening 15 from the interior of the housing 5.

The supply of gas through the tube 22 is 50 designed to be sufficient to maintain the pilot and thermostat in a heated condition so that the parts are as shown in Fig. 1, that is, with the valve 11 in open position. However, if for any reason the pilot should be extinguished, the thermostatic disk will cool off 55 and then suddenly reverse its concavity, drawing the rod 13 to the right and closing the valve as is shown in Fig. 2. To relight the burner it is merely necessary to relight the pilot and the thermostat will when it is 60 again heated snap back to the position shown in Fig. 1, whereupon the valve will be opened and gas may flow to both the pilot and the burner which will enlarge the pilot flame and light the main burner. As the pilot receives 65 an additional supply of gas during the time

the main burner is lighted, it serves as an additional heating gas jet, and at the same time uses little gas to keep the thermostat heated when the main burner is not in operation.

Inasmuch as many modifications of this 70 device may be made without departing from the spirit of the invention, I do not wish to be limited except by the scope of the appended claims.

I claim:

1. The combination with a gas burner and a supply pipe therefor of a pilot burner adapted to light the main gas burner, a valve housing having passages therethrough from said supply pipe to both said main burner and said pilot, a valve in said housing controlling the flow of gas through both of said passages, a thermostat associated with said pilot adapted abruptly to close said valve if said pilot is accidentally extinguished, and a separate additional supply of gas for said pilot by-passing said valve, whereby the pilot is normally lighted irrespective of the main burner.

2. The combination with a gas burner and a supply pipe therefor of a pilot burner adapted to light the main gas burner, a valve housing having passages therethrough from said supply pipe to both said main burner and said pilot, a valve in said housing controlling the flow of gas through both of said passages, a perforated disk thermostat interposed in the gas passage to said pilot and in heat conducting relation with the walls thereof, and a direct connection between the thermostatic disk and said valve, whereby the valve is automatically and abruptly closed if the pilot is extinguished.

3. The combination with a gas burner and a supply pipe therefor of a pilot burner positioned to light the main gas burner, a valve housing having passages therethrough from said supply pipe to both said main burner and said pilot, a valve in said housing controlling the flow of gas through both of said passages, a perforated bi-metallic disk thermostat concentrically mounted in an enlargement of the gas passage to said pilot and in heat conducting relation with the walls of said passage, and a rod having a bearing in said housing connecting the center portion of said thermostatic disk with said valve, whereby the valve is completely and abruptly closed if the pilot is extinguished.

4. The combination with a gas burner and a supply pipe therefor of a pilot burner adapted to light the main gas burner, a valve housing having passages therethrough from said supply pipe to both said main burner and said pilot, a valve in said housing controlling the flow of gas through both of said passages, a cupped perforated bi-metallic disk thermostat concentrically mounted in an enlargement in the gas passage to said pilot and having its periphery in heat con-

ducting relationship with the walls of said burner whenever gas is supplied thereto and enlargement, a rod having a bearing in a whereby said valve is closed completely and part of said housing connecting the center abruptly if the pilot is extinguished. ¹⁰
